US0D1044495S

(12) **United States Design Patent** (10) Patent No.: US D1,044,495 S
Holloway et al. (45) Date of Patent: ** *Oct. 1, 2024

(54) **PACKAGING BOX**

2543/00694; B65D 2543/00805; B65D
2571/0066; B65D 2585/36

See application file for complete search history.

(71) Applicant: **Nicoventures Trading Limited,**
London (GB)

(72) Inventors: **Jack Holloway**, London (GB); **Bo Hu**, Shanghai (CN); **James Pryor**, Maidenhead (GB); **Mark Shane Hatcher**, Winston-Salem, NC (US)

(73) Assignee: **NICOVENTURES TRADING
LIMITED**, London (GB)

(*) Notice: This patent is subject to a terminal disclaimer.

(**) Term: 15 Years

(21) Appl. No.: 29/796,843

(30) **Foreign Application Priority Data**

CLAIM

We claim the ornamental design for a packaging box, as shown.

DESCRIPTION

FIG. 1 is a top perspective view of a packaging box.

FIG. 2 is a bottom perspective view of the packaging box depicted in FIG. 1.

FIG. 3 is a top view of the packaging box depicted in FIG. 1.

FIG. 4 is a bottom view of the packaging box depicted in FIG. 1.

FIG. 5 is a front view of the packaging box depicted in FIG. 1.

FIG. 6 is a rear view of the packaging box depicted in FIG. 1.

FIG. 7 is a right side view of the packaging box depicted in FIG. 1; and,

FIG. 8 is a left side view of the packaging box depicted in FIG. 1.
